LOOM REPLENISHING MECHANISM
George Cadorette, Hopedale, Mass., assignor to Draper
Corporation, Hopedale, Mass., a corporation of Maine
Filed June 21, 1961, Ser. No. 118,628
4 Claims. (Cl. 139—257)

This invention relates to looms for weaving and, more particularly, to an improvement in the mechanism for controlling replenishment of filling bobbins and removal of the tip bunch from such bobbins.

It is a general object of the invention to provide an improved and more positive indicating means for the bobbin replenishing mechanism which includes an extracting device for removing a tip bunch from bobbins prior to transfer of said bobbins into a loom shuttle.

It is a further object of the invention to provide the indicating means of the extracting mechanism with an intermediate motion transferring member for assuring positive indication for tip bunch extraction and a minimization of lost motion.

It is still a further and more specific object of the invention to provide this mechanism with an indicating means which shall be free from interference and which can be adapted for application to various models of looms.

Further objects of the invention will become apparent from the following more detailed disclosure.

In automatic bobbin replenishing looms, such, for example, as the type to employ an automatic battery such as that disclosed in United States Patent No. 2,556,880, it is common practice in many instances to employ bobbins having a finder or tip bunch wound on the end thereof. As disclosed in co-pending application Serial No. 1,201, filed January 8, 1960, now U.S. Patent 3,023,788, the purpose of such a bunch is to permit automatically functioning mechanical means to engage this bunch in a positive manner and to displace it outwardly over the end of the bobbin to be engaged by other means and to be held thereby for a period of time sufficient to permit the transfer to take place and also for the shuttle to make its initial pick through the warp so as to permit the filling to become interlocked in the fabric before the held end of the filling is released.

Satisfactory application of this mechanism has in the past been restricted to relatively few types of looms. This has been due mainly to the difference in design of looms and the different mechanisms associated therewith, which with respect to subject mechanism did not lend themselves for application thereto.

According to the instant invention a novel indicating means which forms a part of the bobbin replenishment mechanism can now be provided which will permit a wider range of application and a more direct and positive indication for actuation of the tip bunch extractor.

The present invention includes an intermediate motion transferring member in the form of a bell crank lever suitably mounted in a bracket attached to the loom side. This bell crank lever is caused to transmit indications imparted to it by means of a Bowden wire one end of which contacts one arm of said lever and the other of which is attached to the transfer mechanism of a loom where such indications are initiated. The second arm of this lever is caused to act upon a floating push rod arrangement which in turn by a camming means actuates the extractor arm lever thus causing the extractor to move endwise over the tip of the bobbin removing the so-called tip bunch therefrom.

The invention will be described in greater detail with reference to the accompanying figures of drawing in which:

2

FIG. 1 is a perspective view of a portion of that side of the loom where replenishment of spent bobbins occurs showing the invention applied thereto;

FIG. 2 is a view of the invention as seen from the front of the loom and looking downwardly at an angle of about 30° more or less;

FIG. 3 is a top view of the bell crank lever showing the wedge shape of its second arm and its relationship with the floating push rod arrangement.

Now referring to the figures of drawing, FIG. 1 shows part of a conventional loom and its motor stand 10 to which there is attached a generally L-shaped mounting bracket 11. Bracket 11 is provided with two generally juxtaposed outwardly directed studs 12 and 13. Stud 13 is adapted to receive thereon in a more or less vertical position an extractor arm lever 14 which is caused to oscillate in a manner hereinafter to be more fully disclosed. It is prevented from moving lengthwise on this stud by means of collar 15 positioned and secured by set screws 16 to the outer end of this stud and adjacent the hub portion of the extractor arm lever.

Stud 12 is adapted to receive thereon a pivotally adjustable bracket generally indicated by numeral 17. Bracket 17 includes a substantially flat, rectangular shaped body portion 18 extending lengthwise of the loom; at each end thereof said body portion is provided with outwardly and oppositely directed arms 19 and 20 and at right angles thereto. Arm 20 of bracket 17 is provided at its outer end with an aperture 21 appropriate for the reception of stud 12. This bracket is firmly held in position and is pivotally adjustable by means of set screws 22 located on the outer end of this arm, which when tightened are caused to bear against stud 12. Arm 19 is in the form of a bolting surface to which there is assembled a downwardly directed generally U-shaped member 23. The U-shape of this member is formed by two outwardly directed arms 24 and 25 in spaced relationship and being provided at their free ends with aligned holes 26 (one only shown in FIGS. 1 and 2).

An intermediate motion transferring member which is in the form of a bell crank lever and indicated generally by numeral 27 is adapted to assemble between arms 24 and 25 by means of a shaft 28 passing through hole 26 of arm 24, thence through the hub portion of said lever and thence through and beyond a corresponding hole (not shown) in arm 25. By means of set screws 29 provided in the hub portion of the bell crank lever 27 this member is firmly secured to shaft 28 and is caused to oscillate in a manner to be more fully explained. That portion of shaft 28 which passes through and beyond arm 25 is provided thereon with a spring casing 30 which houses a torsion spring (not shown) one end of which is fixed to the shaft within said casing and to the other end to arm 25 so as to cause the bell crank lever to be spring biased in a counter clockwise direction, looking from the front of the loom.

The U-shaped member 23 has at its lower side an integrally formed outwardly directed plate-like projection as at 31 having a centrally disposed aperture (not shown) adapted to receive and fixedly position therein one end of a Bowden wire casing 32. A Bowden wire 33 within casing 32 passes through projection 31 to contact a first arm 34 of the bell crank lever 27 which is spring biased in the direction of said wire. The opposite ends of this casing and wire are attached to the transfer mechanism of the loom from which it receives its means of movement upon indication for bobbin replenishment. The bell crank lever 27 includes a second wedge shaped arm 35 which arm, upon indication for bobbin replenishment, is adapted to contact and push outwardly from the loom a floating push rod member 36. Member 36 is assembled within a casing 37 which in turn is fixedly positioned by

means of set screw 38 within a horizontal opening provided in a vertical, forwardly projecting plate-like member 39 integrally formed and positioned beneath the hub portion of the extractor arm lever 14.

The lower portion of the extractor arm lever 14 includes a pair of horizontally extending members 40 and 41 having aligned openings through which there extends a vertical shaft 42. The latter has a spring casing 43 fixed to its lower end which includes a torsion spring (not shown) one end of which is fixed to the casing and the other end to the member 41 thus causing shaft 42 to be urged in a clockwise direction as illustrated by the indicating arrow shown in FIG. 2. The lower end of the stud also includes a collar 44 fixed thereto at a location just above member 41, the collar includes an extension 45 protruding therefrom which rotatably supports a roller member 46. At its upper end shaft 42 has extending horizontally therefrom a flat plate member 47.

Upon call for bobbin replenishment the Bowden wire receives its indication from the loom's transferring mechanism, said wire is caused to move the bell crank lever a short distance whereupon the second arm of said lever forces the floating push rod member outwardly making contact with and causing the flat plate member 47 to move a short distance in a counter clockwise direction. This movement which in turn moves shaft 42 places the roller member 46 into the path of an extractor drive cam 48 that is mounted on an extension 49 of the loom's cam shaft. The roller is engaged by the cam when the lay is approximately at back center and the cam is designed in such a manner and is so timed as to provide clearance for the roller to be swung into and out of its path at that time.

As shown by the directional arrow illustrated in FIG. 1 rotation of cam 48 is in a counter clockwise direction and when engaged by roller 46 causes the extractor arm lever 14 to pivot. This pivoting motion actuates the extractor linkage attached to the upper portion of lever 14 causing the extractor E to move endwise over the bobbin tip removing the tip bunch therefrom.

In operation an indication for bobbin replenishment is conveyed in the conventional manner through the loom's transferring mechanism and these indications are caused to act upon the Bowden wire 33. The bell crank lever being spring biased in the direction of this wire and having one of its arms in contact with the end of said wire is caused to rotate a short distance in a clockwise direction. Excessive movement of this lever is controlled by means of a third arm or stop member S projecting outwardly from the hub portion of said lever and is further controllable by means of an adjusting screw 50 the head of which serves as a contact point for said stop member. Clockwise movement of this lever permits its second wedge shaped arm to contact the floating push rod member thus pushing it outwardly from the loom. The opposite end of this rod contacts the plate member 47 causing the vertical shaft 42 to rotate a distance sufficient to place the roller member 46 into the path of the extractor drive cam 48. The floating push rod member after performing its intended function loses contact with those members acting upon it and which it acts upon, due to the pivot-

ing action of the extractor arm lever, its floating design within the casing 37 and the fact that the bell crank lever's second arm is of wedge shape and spring biased in the opposite direction of said rod.

5 Loss of contact between these members permits the spring biased vertical shaft 42 to swing roller 46 out of the path of the cam after it has performed its intended function.

As heretofore described the roller when placed in the 10 path of the cam causes the extractor arm lever to pivot thus transmitting this motion to the extractor E by means of its linkage attached to the upper portion of said lever and as it moves it endwise over the bobbin tip the extractor removes the tip bunch therefrom.

15 While one embodiment of the invention has been disclosed, it is to be understood that the inventive concept may be carried out in a number of ways. This invention is, therefore, not to be limited to the precise details described, but is intended to embrace all variations and 20 modifications thereof falling within the spirit of the invention and the scope of the claims.

I claim:

1. In combination in a loom for weaving a bobbin feeding means for retaining and presenting for transfer to 25 a loom shuttle a supply of bobbins having filling wound thereon an end of which is wound in the form of a tip bunch adjacent the bobbin end, a tip bunch extractor, a cam follower member, camming means for moving said tip bunch extractor endwise over the end of said bobbin, 30 an intermediate motion transferring member, a transfer indicating means effective only on indication for bobbin replenishment upon said member, a further means effective by said intermediate motion transfer member for moving said follower member into the path of said camming means thus actuating said extractor to remove said tip bunch from said bobbin end.

2. The mechanism of claim 1 wherein said intermediate motion transferring member includes a bell crank lever spring biased in the direction of said indicating means.

40 3. The mechanism of claim 2 wherein said spring biased bell crank lever includes one arm in spring contact with said indicating means, and a second arm effective only on indication for replenishment of said bobbin on a floating push rod member for causing said cam means to actuate said extractor, a third arm with means for adjustment to prevent overthrow of said bell crank lever, said second arm being adapted to lose contact with said floating push rod member after initiation of said camming means for actuating said extractor.

45 4. The mechanism of claim 3 wherein said indicating means includes a Bowden wire having a casing one end of which is fixedly mounted adjacent said bell crank lever.
